No. 656,704.

Patented Aug. 28, 1900.

W. D. SNYDER.

COMBINED SASH FASTENER AND LIFT.

(Application filed, Jan. 13, 1900.)

(No Model.)

UNITED STATES PATENT OFFICE.

WILLIAM D. SNYDER, OF GRACEDALE, PENNSYLVANIA.

COMBINED SASH FASTENER AND LIFT.

SPECIFICATION forming part of Letters Patent No. 656,704, dated August 28, 1900.

Application filed January 13, 1900. Serial No. 1,357. (No model.)

To all whom it may concern:

Be it known that I, WILLIAM D. SNYDER, a citizen of the United States, residing at Grace-
dale, in the county of Luzerne and State of
Pennsylvania, have invented certain new and
useful Improvements in a Combined Sash Fast-
ener and Lifter, of which the following is a
specification.

My invention relates to a combined sash
fastener and lifter adapted especially for
car-windows, but capable for use upon win-
dows generally, the object being to provide a
simple and inexpensive device of the char-
acter named which will serve the double pur-
pose of locking the sash and furnishing a con-
venient means for raising the same.

The construction of the improvement will
be fully described hereinafter and defined in
the appended claim, in connection with the
accompanying drawings, which form a part of
this specification, and in which—

Figure 1 is a front elevation of a portion of
a window frame and sash with my improved
fastener and lifter applied thereto, and Fig.
2 is an elevation of the combined fastener and
lifter detached from the sash and having its
cap-plates removed to show the mechanism.

The reference - numeral 1 designates the
lower rail of a window-sash to which are se-
cured two casings or housings 2 and 3. The
casing 2 is provided with a horizontal recess
4 to receive a bolt 5, the outer end of which
is adapted to enter a socket or recess 6, formed
in the side of the window-frame.

From the upper side of the bolt 5 projects
a lug 7, which bears against a shoulder 8 of
the casing 2, a spiral spring 9 being interposed
between the lug 7 and a shoulder 10 of the
casing.

To the outer end of the bolt 5 is secured one
end of a rod 11, which projects through the
casing and through a guide-bracket 12 into
the casing 3, the end of said rod within the
casing 3 being turned upward to form a hook
13, which engages a rounded lug 14, formed
on the lower end of a finger-piece 15, curved
at its upper end and adapted to move in a ver-

tical recess 16, formed in the casing 3. A lat-
erally-extending recess 17 is formed in the cas-
ing 3 to allow the required longitudinal move-
ment of the rod 11.

18 designates a curved thumb-plate secured
to the sash back of the finger-piece 15.

The casings 2 and 3 are closed by suitable
plates 19.

The utility and operation of the parts will
be readily understood. Normally the spring
9 projects the bolt 5 into the recess 6 of the
frame to lock the window. By grasping the
curved pieces 15 and 18 between the thumb 60
and finger the finger-piece 15 is raised, thus
withdrawing the bolt through the intermedi-
acy of the rod 11, after which the sash may
be conveniently raised by an upward pressure
upon the parts 15 and 18.

It will be apparent that the simplicity of
the parts avoids the liability of breakage or
disarrangement and that the bolt will spring
back to lock the sash as soon as the latter is
lowered.

I claim—

The combination with a window-sash, of a
combined fastener and lifter, comprising a
casing secured to the lower rail of the sash
and formed with a bolt-recess, and with shoul-
ders 8 and 10; a second casing secured to the
sash formed with a vertical recess 16 and a
lateral recess 17; a bolt within the recess of
the first-named casing formed with a project-
ing lug; a spring between said lug and the
shoulder 10; a rod secured at one end to said
bolt, and having its other end extended into
the adjacent casing and bent to hook form;
a movable finger-piece supported in the recess
16 and having a curved projection which is
engaged by the hooked end of the rod; and
a fixed thumb-piece overhanging the finger-
piece.

In testimony whereof I affix my signature
in presence of two witnesses.

WILLIAM D. SNYDER.
